(57) **ABSTRACT**

A compressor for a commercial vehicle comprises: a plurality of cylinders, wherein each cylinder accommodates a reciprocating piston, wherein the reciprocating piston is driven by a crankshaft, and a plurality of cooling means, arranged at a cylinder head region of the cylinder, wherein one specific cooling means is assigned to one cylinder respectively. The compressor assembly comprises a sensor network, wherein the sensor network comprises a plurality of temperature sensitive switches, wherein each temperature sensitive switch is assigned to a cylinder.

COMPRESSOR ASSEMBLY, AIR SUPPLY
SYSTEM, VEHICLECROSS-REFERENCE TO RELATED
APPLICATIONS

This application is the U.S. National Stage of PCT/EP2022/077517 filed on 4 Oct. 2022, which claims priority to Chinese Patent Application No. 202111202363.X filed on 15 Oct. 2021, the content of which is incorporated herein by reference.

The invention relates in a first aspect to a compressor assembly for a commercial vehicle according to the preamble of claim 1. The invention further relates in a second aspect to an air supply system and in a third aspect to a vehicle comprising a compressor assembly according to the first aspect and/or an air supply system according to the second aspect of the invention.

Compressors and compressor assemblies for commercial vehicles are generally well known. Compressor assemblies comprise at least one compressor, such as a reciprocating compressor, for providing pressurized air to an air supply system and/or other pneumatic systems of the vehicle.

Regarding compressor assemblies, it is generally desirable to obtain a reliable and safe operation. During the operation of a compressor assembly, it is desirable to detect unfavorable operating conditions and faults at an early stage to prevent downtime and/or further damage of the compressor assembly.

CN210290104U describes in a general manner a diagnosis system for a piston of a reciprocating compressor, and specifically relates to the technical field of compressor piston diagnosis, including a controller. The system described therein is adapted to detect the temperature of a piston activity environment through a temperature sensor.

Despite such generally favorable approaches, compressors and compressor assemblies can still be improved, in particular with respect to reliability and with respect to an effective monitoring means.

It is therefore desirable to address at least one of the above problems.

This is where the invention comes in, with the object to specifically improve compressor assemblies with respect to reliability and with respect to an effective monitoring means.

In accordance with the invention, the object is solved in a first aspect by a compressor assembly as proposed according to claim 1. In accordance with the invention, a compressor assembly is proposed, in particular for a commercial vehicle, comprising a plurality of cylinders, wherein each cylinder accommodates a reciprocating piston, wherein the reciprocating piston is operatively coupled to a crankshaft, and a plurality of cooling means, preferably a plurality of fans, arranged at a cylinder head region of the cylinder, wherein one specific cooling means is assigned to one cylinder respectively.

According to the invention, it is proposed that the compressor assembly comprises a sensor network, comprising a plurality of temperature sensitive switches, wherein each temperature sensitive switch is assigned to a cylinder, and each temperature sensitive switch comprises a first electric terminal and a second electric terminal and is adapted to switch from a closed position to an open position, in which an electric connection between the first electric terminal and the second electric terminal is interrupted when a switch temperature at the temperature sensitive switch is exceeded,

2

and the sensor network is adapted to provide an overheat signal when at least one temperature sensitive switch is in the open position.

The invention is based on the finding that a temperature sensitive switch, that is assigned to a cylinder, is an effective means of monitoring said cylinder and/or the compressor assembly. The invention has recognized that, by being adapted to interrupt the electric connection between the first and the second electric terminal when a switch temperature is reached or exceeded, such temperature sensitive switch is a simple but effective detecting means. In other words, the temperature sensitive switch provides a simple but effective detecting function that indicates whether the switch temperature has been reached or exceeded by interrupting said electric connection.

Because the temperature sensitive switch is assigned to a cylinder, a possible fault in or at the piston and/or the cylinder can be detected in a relatively early stage, in particular because such fault will result in an increased temperature in the region of the cylinder. Such fault can be, among other things, the failure of a cooling means assigned to the corresponding cylinder. By detecting such fault in an early stage, further damage of the compressor can be prevented.

A temperature sensitive switch advantageously provides a relatively simple temperature sensing means, in particular because no sophisticated signal processing equipment is required. There is an open position and a closed position of the temperature sensitive switch, wherein an electric connection is established when the closed position is engaged. Therefore, it can be determined whether a switch temperature has been reached or exceeded in dependence of the presence of a measurement current and/or measurement voltage.

The sensor network is therefore adapted to detect whether a switch temperature at a cylinder has been reached or exceeded. This is particularly advantageous for determining whether the cooling means at the corresponding cylinder is functioning properly.

A sensor network in this context is considered any configuration comprising at least two temperature sensitive switches that are connected in the form of an electric circuit and that is adapted to provide an overheat signal when at least one temperature sensitive switch is in the open position.

Further developments of the invention can be found in the dependent claims and show particularly advantageous possibilities to realize above described concept in light of the object of the invention and regarding further advantages.

Preferably, several or all reciprocating pistons are operatively coupled to the same crankshaft.

Preferably, an individual temperature sensitive switch is assigned to each cylinder of the compressor assembly. In such configuration, the sensor network comprises a temperature sensitive switch for each cylinder of the compressor assembly. Consequently, the temperature at each cylinder can be monitored. Preferably, the compressor assembly is a reciprocating compressor assembly. Preferably, the sensor network is adapted to provide an overheat signal if a measurement current and/or measurement voltage changes, in particular if a measurement current and/or measurement voltage is absent.

In preferred developments, the sensor network further comprises a first temperature sensing device configured to determine a motor temperature at a motor, in particular an electric motor, of the compressor assembly. In further preferred developments, the sensor network further comprises

a second temperature sensing device, configured to determine a power electronics temperature at a power electronics unit of the compressor assembly. Preferably, the first temperature sensing device and/or the second temperature sensing device are configured as temperature sensitive switches, in particular so that they can be integrated into the sensor network along with the other temperature sensitive switches that are assigned to the cylinders. Preferably, the first temperature sensing device is configured as a temperature sensitive switch adapted to switch into an open position when a further switch temperature has been reached or exceeded. Preferably, the second temperature sensing device is configured as a temperature sensitive switch adapted to switch into an open position when an even further switch temperature has been reached or exceeded.

In a further preferred development, the compressor assembly comprises an electric motor, adapted to drive the crankshaft. Preferably, the temperature sensitive switch comprises a contact bridge, wherein the contact bridge comprises a first material layer with a first temperature coefficient, and a second material layer with a second temperature coefficient. The first and second material layers are preferably attached to each other resulting in an opening movement substantially perpendicular to the material layer when the temperature changes. In a further preferred development, the temperature sensitive switch is a bimetallic switch. Preferably, all temperature sensitive switches of the sensor network are bimetallic switches. Bimetallic switches are a simple and reliable means for detecting whether a switch temperature has been reached or exceeded. A bimetallic switch preferably comprises a first metallic material layer with a first temperature coefficient and a second metallic material layer with a second temperature coefficient.

A preferred development suggests that the switch temperature is defined to be in a range from 140° C. to 260° C., preferably from 180° C. to 220° C., more preferably 200° C. In other developments, deviating switch temperatures are possible. However, the ranges indicated above have been proven to reliably monitor the operation of the compressor assembly, in particular to indicate whether a cooling means at a specific cylinder has failed to operate.

In accordance with a further development, it is proposed that the temperature sensitive switch is arranged in the cylinder head region or between the cylinder head region and the cooling means. Arranging the temperature sensitive switch near the cylinder head region has the advantage of achieving a quick response to any increase in temperature in said cylinder head. Further, by being close to the cooling means, in particular to the fan, of a cylinder, a failure or fault of said cooling means can be detected by an increase in temperature through the temperature sensitive switch.

In a preferred development, the temperature sensitive switches of the sensor network are electrically connected in series, and the sensor network is configured to provide the overheat signal if a measurement voltage and/or a measurement current is not present at a measurement terminal. In such development, the temperature sensitive switches are preferably connected to each other in a serial electric circuit. Such development advantageously provides a simple yet reliable means of detecting a default or failure in the compressor assembly, in particular whether one or more cooling means have broken down.

In a preferred development, the temperature sensitive switches of the sensor network are electrically connected in parallel, wherein each temperature sensitive switch is arranged in a parallel branch of the sensor network, and a

measurement terminal is arranged in one of the parallel branches, and the sensor network is configured to provide the overheat signal if a measurement current at the measurement terminal changes. In such development, the temperature sensitive switches are preferably connected to each other in a parallel electric circuit.

Preferably, at least two parallel branches comprise a resistor with a resistance, wherein a first resistance of a first resistor in a first parallel branch differs from a second resistance of a second resistor in a second parallel branch. Preferably, all parallel branches comprise a resistor, or all parallel branches except one parallel branch comprises a resistor. Preferably, each resistor has an individual resistance, differing from the resistance of all other resistors. Based on the principle of a current divider, it is advantageously possible to identify which parallel branch comprises a temperature sensitive switch that is in an open position. The term "resistance" is considered as a resistance value, preferably expressed in the unit "Ohm", as a property of the corresponding resistor.

In accordance with a further development, it is proposed that the overheat signal is representative for the measurement current at the measurement terminal of the temperature sensitive switch where the switch temperature is exceeded. Preferably, the signal processing unit is configured to provide an individual overheat signal in dependence of a measurement current and/or measurement voltage that is determined at the measurement terminal. In such a development of the invention, it is advantageously possible to distinguish at which cylinder the switch temperature has been reached or exceeded. According to the measurement current and/or the measurement voltage, the according parallel branch comprising a temperature sensitive switch in an open position can be identified. In particular, this is achieved based on the current divider principle and according to the individual resistance values.

In a preferred development, the sensor network comprises a signal processing unit, adapted to provide the overheat signal in dependence of the measurement voltage and/or a measurement current, wherein preferably the signal processing unit is connected to an electronic control unit of the vehicle. In particular, the signal processing unit is adapted to provide an overheat signal if the measurement current and/or measurement voltage changes or if the measurement current and/or measurement voltage is absent. Preferably, the signal processing unit is adapted to provide an individual overheat signal assignable to a specific cylinder in dependence of the value of the measurement current and/or measurement voltage.

In a second aspect of the invention, an air supply system for a vehicle, comprising a compressor assembly according to the first aspect of the invention. Preferably, the air supply system comprises at least one pneumatic consumer, in particular a pneumatic brake system and/or an air suspension system and/or a sensor cleaning system.

In a third aspect of the invention, a vehicle, preferably commercial vehicle, is proposed, comprising a compressor assembly according to the first aspect of the invention and/or an air supply system according to the second aspect of the invention.

In a preferred development of the vehicle, an electronic control unit is proposed that is connected to the sensor network, in particular to a signal processing unit, and is adapted to receive an overheat signal and to provide an alarm indication via an alarm indication device, preferably to display an alarm message, in dependence of the overheat signal.

It shall be understood that the compressor assembly according to the first aspect of the invention, the air supply system according to the second aspect of the invention and the vehicle according to the third aspect of the invention comprise identical or similar developments, in particular as described in the dependent claims. Therefore, a development of one aspect of the invention is also applicable to another aspect of the invention.

These and other aspects of the invention will be apparent from and elucidated with reference to the embodiments described hereinafter. The embodiments of the invention are described in the following on the basis of the drawings in comparison with the state of the art, which is also partly illustrated. The latter is not necessarily intended to represent the embodiments to scale. Drawings are, where useful for explanation, shown in schematized and/or slightly distorted form. With regard to additions to the lessons immediately recognizable from the drawings, reference is made to the relevant state of the art. It should be borne in mind that numerous modifications and changes can be made to the form and detail of an embodiment without deviating from the general idea of the invention. The features of the invention disclosed in the description, in the drawings and in the claims may be essential for the further development of the invention, either individually or in any combination.

Further advantages, features and details of the invention result from the following description of the preferred embodiments as well as from the drawings, which show in:

FIG. 1A an illustration of a temperature sensitive switch in the form of a bimetallic switch in a closed position for an compressor assembly according to the first aspect of the invention,

FIG. 1B an illustration of a temperature sensitive switch in the form of a bimetallic switch in an open position for an compressor assembly according to the first aspect of the invention,

FIG. 2A a schematic illustration of a first preferred embodiment of a compressor assembly with a first sensor network,

FIG. 2B a schematic illustration of a second preferred embodiment of a compressor assembly with a second sensor network,

FIGS. 3A, 3B a front view and a side view of a compressor assembly according to the first aspect of the invention, which preferably can be configured as the first or the second preferred embodiment of the compressor assembly,

FIG. 4 A schematic illustration of a vehicle according to the third aspect of the invention, comprising an air supply system according to the second aspect of the invention.

FIG. 1A shows an illustration of a temperature sensitive switch 110 in a closed position 110A. The temperature sensitive switch 110 comprises a contact bridge 115, adapted to electrically connect a first electric terminal 112 with a second electric terminal 114. The contact bridge 115 comprises a first material layer 116 with a first temperature coefficient TC1, and a second material layer 118 with a second temperature coefficient TC2. The first material layer 116 is attached to the second material layer 118, preferably by means of an adhesive or a welded connection, or by means of other bonding techniques such as rolling. The first material layer 116 and/or the second material layer 118 are preferably made of metallic materials. The contact bridge 115 is adapted to open and close an electric connection between the first electric terminal 112 and the second electric terminal 114 at a contact point K in dependence of a switch temperature TS. In the closed position 110A, the contact bridge 115 is in contact with a contact foundation

119, establishing an electric connection between the first electric terminal 112 and the second electric terminal 114. In other words, the contact point K is the point of contact between the contact bridge 115 and the contact foundation 119.

FIG. 1B shows the temperature sensitive switch 110 shown in FIG. 1A, but in an open position 110B. The open position 110B is established when a temperature T at the temperature sensitive switch 110, in particular at the contact bridge 115, reaches or exceeds the switch temperature TS, in particular due to a heat flow H. In particular, the heat flow H is emitted by a piston and/or cylinder of a compressor assembly not shown here. The heat flow H tends to increase when a cooling means (not shown in FIG. 1A and FIG. 1B), assigned to the same cylinder as the temperature sensitive switch 110, is not operating. The contact bridge 115 is adapted to lift from the contact foundation 118 in an opening movement MO. The contact bridge 115 is configured to perform the opening movement MO, since the second temperature coefficient TC2 is greater than the first temperature coefficient TC1, resulting in a bending of the contact bridge 115 in a direction that is substantially perpendicular to the contact bridge 115. A greater temperature coefficient TC means a greater expansion when subjected to heat. The greater the difference between the first temperature coefficient TC1 and the second temperature coefficient TC2, the greater the amplitude of the opening movement MO. Preferably, the switch temperature TS is in the range from 140° C. to 260° C., more preferably from 180° C. to 220° C., even more preferably 200° C.

The temperature sensitive switch 110 is in the form of a bimetallic switch 111. In other embodiments, the temperature sensitive switch 110 can be of another configuration, for example comprising other materials than metallic materials.

FIG. 2A shows a schematic illustration of a first preferred embodiment of a compressor assembly 100. The compressor assembly 100 comprises a first sensor network 200 with a plurality of four temperature sensitive switches 110, namely a first temperature sensitive switch 110.1, a second temperature sensitive switch 110.2, a third temperature sensitive switch 110.3 and a fourth temperature sensitive switch 110.4. Each temperature sensitive switch 110 shown here is configured as a bimetallic switch 111.

The temperature sensitive switches 110.1, 110.2, 110.3, 110.4 are connected in series by means of a serial electric circuit 246. This means, that a first electric terminal 112.1 of the first temperature sensitive switch 110.1 is connected to a first source terminal 242 of an electric source 240. A second electric terminal 114.1 of the first temperature sensitive switch 110.1 is connected to a first electric terminal 112.2 of the second temperature sensitive switch 110.2. A second electric terminal 114.2 of the second temperature sensitive switch 110.2 is connected to a first electric terminal 112.3 of the third temperature sensitive switch 110.3. A second electric terminal 114.3 of the third temperature sensitive switch 110.3 is connected to a first electric terminal 112.4 of the fourth temperature sensitive switch 110.4. A second electric terminal 114.4 of the fourth temperature sensitive switch 110.4 is connected to a second source terminal 244 of the electric source 240. Optionally, a fifth temperature sensitive switch 110.5 and/or a sixth temperature sensitive switch 110.6, or more temperature sensitive switches 110, can be additionally integrated, as indicated here.

The electric source 240 is adapted to provide a measurement voltage UM and/or a measurement current IM between the first source terminal 242 and the second source terminal

244. The first temperature sensitive switch **110.1** is assigned to a first cylinder **140.1** of the compressor assembly **200**. Preferably, the first temperature sensitive switch **110.1** is located at or near the first cylinder **140.1**, such as here between a first cylinder head region **142.1** of the first cylinder **140.1** and a first cooling means **160.1** (not shown here) assigned to the first cylinder **140.1**. When a first temperature **T1** reaches or exceeds the switch temperature **TS**, the first temperature sensitive switch **110.1** switches from a closed position **110A** to an open position **110B**, such as described in FIG. 1A and FIG. 1B.

The above description referring to the first temperature sensitive switch **110.1** and the first cylinder **140.1** applies in an analog manner with corresponding numbering to the second, third and fourth temperature sensitive switch **110.2**, **110.3**, **110.4** as well as the second, third and fourth cylinder **140.2**, **140.3**, **140.4**, respectively.

The sensor network **100** further comprises a signal processing unit **210**, adapted to provide an overheat signal **SO** in dependence of the measurement voltage **UM** and/or the measurement current **IM**. In the embodiment shown here, the signal processing unit **210** is connected to the serial electric circuit **246** by means of a measurement terminal **230** and is adapted to detect the measurement current **IM**. The measurement terminal **230** is connected in series between the first source terminal **242** and the first electric terminal **112.1** of the first temperature sensitive switch **110.1**.

The signal processing unit **210** is adapted to provide the overheat signal **SO** if no measurement current **IM** is detected. This is the case, if at least one of the temperature sensitive switches **110.1**, **110.2**, **110.3**, **110.4** is in an open position **110B**, because the corresponding temperature **T1**, **T2**, **T3**, **T4** has reached or exceeded the switch temperature **TS**, and consequently the serial electric circuit **246** is interrupted.

FIG. 2B shows a second preferred embodiment of a further compressor assembly **100'**, comprising a further sensor network **200'** with a parallel arrangement of temperature sensitive switches **110**. Each temperature sensitive switch **110** is arranged in a parallel branch **180**. In the embodiment shown, the sensor network **200'** comprises a plurality of four temperature sensitive switches **110**, namely a first temperature sensitive switch **110.1**, second temperature sensitive switch **110.2**, a third temperature sensitive switch **110.3** and a fourth temperature sensitive switch **110.4**, each arranged in a corresponding first to fourth parallel branch **180.1**, **180.2**, **180.3**, **180.4**. The parallel branches **180.1**, **180.2**, **180.3**, **180.4** together form a parallel electric circuit **248**. Optionally, the further sensor network **200'** can comprise further parallel branches **180**, such as a fifth parallel branch **180.5** with a fifth temperature sensitive switch **110.5** and a fifth resistor **170.5**, and/or a sixth parallel branch **180.6** with a sixth temperature sensitive switch **110.6** and a sixth resistor **170.6**.

Due to the layout with parallel branches **180.1**, **180.2**, **180.3**, **180.4**, the sensor network **200'** of the embodiment shown advantageously provides the function of a current divider. When one of the temperature sensitive switches **110.1**, **110.2**, **110.3**, **110.4** is in an open position **110B**, and the measurement current **IM1**, **IM2**, **IM3**, **IM4** in the corresponding parallel branch **180.1**, **180.2**, **180.3**, **180.4** is interrupted, the measurement current **IM1**, **IM2**, **IM3**, **IM4** in all other, non-interrupted parallel branches **180.1**, **180.2**, **180.3**, **180.4** will change, enabling the identification of the parallel branch **180.1**, **180.2**, **180.3**, **180.4** where the measurement current **IM** is interrupted. Accordingly, the corresponding parallel branch **180.1**, **180.2**, **180.3**, **180.4**, where

the temperature sensitive switch **110** is in its open position **110R**, can be identified by detecting one of the measurement currents **IM1**, **IM2**, **IM3**, **IM4**.

In the shown embodiment, each parallel branch **180.1**, **180.2**, **180.3**, **180.4** comprises a corresponding electric resistor **170.1**, **170.2**, **170.3**, **170.4** each with a corresponding resistance value **R1**, **R2**, **R3**, **R4**, wherein each resistance value **R1**, **R2**, **R3**, **R4** is different from the other resistance values **R1**, **R2**, **R3**, **R4** in terms of its Ohmic value. For example, the resistance values **R1**, **R2**, **R3**, **R4** can have the relation **R1 < R2 < R3 < R4**.

The first measurement current **IM1** in the corresponding first parallel branch **180.1** can be determined as follows:

$$IM1 = IT * \frac{R1}{R1 + R2 + R3 + R4}$$

When the first temperature sensitive switch **110.1** switches to its open position **110B**, the first measurement current **IM1** will be zero, as the first parallel branch **180.1** is interrupted. If one of the other temperature sensitive switches **110.2**, **110.3**, **110.4** switches to its open position **110B**, the corresponding other measurement current **IM2**, **IM3**, **IM4** will be zero. For example, if the fourth temperature sensitive switch **110.4** switches to its open position **110B**, the fourth parallel branch **180.4** will be interrupted and the fourth resistor **170.4** with its fourth resistance value **R4** will be rendered ineffective. In such case, the first measurement current would be determined as follows:

$$IM1' = IT * \frac{R1}{R1 + R2 + R3}$$

Hence, the further measurement current **IM1'** is greater than the measurement current **IM1** above, since the total current **IT** is distributed on fewer parallel branches **180.1**, **180.2**, **180.3**. Because of the individual, different resistance values **R1**, **R2**, **R3**, **R4**, it can be detected for each cylinder **140.1**, **140.2**, **140.3**, **140.4** individually, whether the corresponding temperature sensitive switch **110.1**, **110.2**, **110.3**, **110.4** has switched to its open position **110B**. In the embodiment shown in FIG. 2B, the signal processing unit **210** is connected to the parallel electric circuit **248** via a measurement terminal **230** electrically connected to the fourth parallel branch **180.4**. Consequently, the fourth measurement current **IM4** determined by the signal processing unit **210** will be zero when the fourth temperature sensitive switch **110.4** is in its open position **110B**.

When the first temperature sensitive switch **110.1** is in its open position **110B**, the fourth measurement current **IM4** will be as follows:

$$IM4' = IT * \frac{R4}{R2 + R3 + R4}$$

When the second temperature sensitive switch **110.2** is in its open position **110B**, the fourth measurement current **IM4** will be as follows:

$$IM4'' = IT * \frac{R4}{R1 + R3 + R4}$$

When the third temperature sensitive switch **110.3** is in its open position **110B**, the fourth measurement current **IM4** will be as follows:

$$IM4' = IT * \frac{R4}{R1 + R2 + R4}$$

Hence, it can be individually determined for each cylinder **140.1**, **140.2**, **140.3**, **140.4**, whether the corresponding temperature **T1**, **T2**, **T3**, **T4** has reached or exceeded the switch temperature **TS**, and a first to fourth overheat signal **SO1**, **SO2**, **SO3**, **SO4** can be output accordingly.

Even more, also if a combination of several temperature sensitive switches **110.1**, **110.2**, **110.3**—given that they are arranged in parallel branches **180.1**, **180.2**, **180.3** not comprising the measurement terminal **230**—switch to the open position **110B**, such combination can be determined by an individual value of the fourth measurement current **IM4**.

In other embodiments, the measurement terminal **230** can be connected to any other parallel branch **180.1**, **180.2**, **180.3** of the sensor network **200**.

In optional embodiments, the sensor network **200** or the further sensor network **200'** can comprise further temperature sensitive switches **110**, in particular a fifth temperature sensitive switch **110.5** and/or a sixth temperature sensitive switch **110.6**, as further described in the context of FIG. 3A and FIG. 3B.

FIG. 3A shows a preferred embodiment of a compressor assembly **200** in the form of a reciprocating compressor **202**, comprising an amount of four cylinders **140.1**, **140.2**, **140.3**, **140.4** in a front view, with the first cylinder **140.1** and the second cylinder **140.2** visible. The first cylinder **140.1** and the fourth cylinder **140.4** are arranged in a first V-shaped configuration **V1**. In an analog manner, the second cylinder **140.2** and the third cylinder **140.3** are also arranged in a second V-shaped configuration **V2**, as also visible in the side view of FIG. 3B. The compressor assembly **200** is driven by an electric motor **250**, which is located symmetrically in between the first V-shaped configuration **V1** and the second V-shaped configuration **V2**. In FIG. 3B, a third reciprocating piston **150.3** assigned to the third cylinder **140.3**, as well as the crankshaft **154** are visible in an exemplary cut out view.

A cooling means **160** in the form of a fan **162** is assigned to each cylinder **140**. Consequently, a first cooling means **160.1** in the form of a first fan **162.1** is assigned to the first cylinder **140.1**. The first cooling means **160.1** is arranged on a first cylinder head region **142.1** of the first cylinder **140.1**. The first temperature sensitive switch **110.1** comprises a first electric terminal **112.1** and a second electric terminal **140.1**. The first temperature sensitive switch **110.1** is arranged at the first cylinder head region **142.1**, in between the first cylinder head region **142.1** and the first cooling means **160.1**.

The first temperatures sensitive switch **110.1** is adapted to switch to an open position **110B** when a first temperature **T1** reaches or exceeds a switch temperature **TS**, as described in FIG. 1A and FIG. 1B. This is particularly the case when the first cooling means **160.1** stops operating or is operating in an abnormal operating mode, in particular with reduced efficiency.

The above description referring to the first temperature sensitive switch **110.1** and the first cylinder **140.1** applies in an analog manner to the second, third and fourth temperature sensitive switch **110.2**, **110.3**, **110.4** as well as the second, third and fourth cylinder **140.2**, **140.3**, **140.4**, respectively.

In particular, the compressor assembly **100** shown in FIG. 3A and FIG. 3B can comprise a sensor network **200** as shown in FIG. 2A or alternatively, a sensor network **200'** as shown in FIG. 2B. In particular, the according sensor network **200**, **200'** can be achieved by the corresponding wiring of each first electric terminal **112** and each second electric terminal **114** of the temperature sensitive switches **110**.

The compressor assembly **200** can optionally comprise a first temperature sensing device **122**, configured to determine a motor temperature **TM** at the electric motor **250**. Preferably, the first temperature sensing device **122** can be in the form of a fifth temperature sensitive switch **110.5**, adapted to switch into an open position **110B** when a further switch temperature **TS2** is reached or exceeded. Depending on the architecture of the sensor network **200**, **200'**, the fifth temperature sensitive switch **110.5** can be arranged in series with the other temperature sensitive switches **110** in a serial electrical circuit **246**, or in a fifth parallel branch **180.5** in a parallel electrical circuit **248**.

The compressor assembly **200** can optionally comprise a second temperature sensing device **124**, configured to determine a power electronics temperature **TP** at a power electronics unit **260**. In particular, the power electronics unit **260** can be in the form of or comprise an inverter **262**, as shown in FIG. 3B. Preferably, the second temperature sensing device **124** can be in the form of a sixth temperature sensitive switch **110.6**, adapted to switching to an open position **110** be when an even further switch temperature **TS3** is reached or exceeded. Depending on the architecture of the sensor network **200**, **200'**, the sixth temperature sensitive switch **110.6** can be arranged in series with the other temperature sensitive switches **110** in a serial electrical circuit **246**, or in a sixth parallel branch **180.6** in a parallel electrical circuit **248**.

FIG. 4 shows a schematic view of a vehicle **1000** comprising a compressor assembly **100** according to the concept of the invention. The vehicle **1000** can be a conventional combustion vehicle **1001** with a drive means **1100** in the form of a combustion engine **1101**. In other embodiments, the vehicle **1000** can be an electric vehicle **1002**, with drive means **1100** in the form of one or more electric drive motors **1102**. In again other embodiments, the vehicle **1000** can be a hybrid vehicle **1004**, with a drive means **1100** combining a combustion engine **1101** and one or more electric drive motors **1102**. The drive means **1100** is adapted to provide a drive motion **MD** for propelling the vehicle **1000**.

The vehicle **1000** further comprises an electric energy source **1200**, in particular a vehicle battery **1202** such as a traction battery **1204** and/or a system supply battery **1206**. In other embodiments, the electric energy source **1200** can alternatively or additionally comprise a fuel cell **1208**. The electric energy source **1200** is adapted to provide electric energy **E** to the one or more electric drive motors **1102** and/or the electric motor **250** of the compressor assembly **200**. Independent of the mode of propulsion, the vehicle **1000** can be a commercial vehicle **1012** or a passenger vehicle **1014**.

The depicted vehicle **1000** exemplarily comprises two axles **530**, a front axle **532** and a rear axle **534**. Wheels **540** are attached to the front axle **532** as well as to the rear axle **534**. In other embodiments, the drivetrain can be different, such as an individual electric motor **1102** assigned to each axle **530** or wheel **540**. In other embodiments, the number of axles **530** and wheels **540** can vary.

The vehicle **1000** comprises an air supply system **800** with a compressor assembly **100**. The main components of

11

the compressor assembly 100 are shown schematically, with a rotational axis AR of the crankshaft 154 indicated. The orientation of the rotational axis AR and thus, the modular compressor assembly 100, can vary depending on the available space and installation position in the vehicle 1000, and is here—as an example—substantially parallel to the vehicle 1000.

The air supply system comprises at least one pneumatic consumer 810, such as a pneumatic brake system 812 and/or an air suspension system 814 and/or a sensor cleaning system 816.

The signal processing unit 210 of the sensor network 100 is configured to communicate with an electronic control unit 700 of the vehicle 1000, in order to provide an overheat signal SO to the electronic control unit 700. In particular, the signal processing unit 210 is connected to the electronic control unit 700 by means of a signal line 740.

The electronic control unit 700 is again configured to provide an alarm indication 722 in dependence of the overheat signal SO. The vehicle 1000 can comprise an alarm indication device 720, adapted to output the alarm indication 722. The alarm indication device 720 is preferably adapted to output an alarm message 724 and for this purpose can comprise a display screen. In other embodiments, the alarm indication device 720 can comprise other indication devices, such as a lightbulb, an audio speaker or the like output means for indicating a visual and/or aural alarm indication 722.

The invention claimed is:

1. A compressor assembly for a commercial vehicle, comprising:
  - a plurality of cylinders, wherein each cylinder accommodates a reciprocating piston, wherein the reciprocating piston is operatively coupled to a crankshaft, and
  - a plurality of cooling means arranged at a cylinder head region of the cylinder, wherein one specific cooling means is assigned to one cylinder, respectively, wherein the compressor assembly comprises:
    - a sensor network comprising a plurality of temperature sensitive switches, wherein:
      - each temperature sensitive switch is assigned to a cylinder, and
      - each temperature sensitive switch comprises a first electric terminal and a second electric terminal and is adapted to switch from a closed position to an open position in which an electric connection between the first electric terminal and the second electric terminal is interrupted when a switch temperature at the temperature sensitive switch is reached or exceeded, and the sensor network is adapted to provide an overheat signal when at least one temperature sensitive switch is in the open position.
2. A compressor assembly according to claim 1, wherein the sensor network further comprises a first temperature sensing device configured to determine a motor temperature at an electric motor of the compressor assembly and/or a second temperature sensing device, configured to determine a power electronics temperature at a power electronics unit of the compressor assembly.
3. A compressor assembly according to claim 1, wherein the compressor assembly comprises an electric motor, adapted to drive the crankshaft.

4. A compressor assembly according to claim 1, wherein the temperature sensitive switch is a bimetallic switch.
5. A compressor assembly according to claim 1, wherein the switch temperature is defined to be in a range from 140° C. to 260° C.
6. A compressor assembly according to claim 1, wherein the temperature sensitive switch is arranged in the cylinder head region or between the cylinder head region and the cooling means.
7. A compressor assembly according to claim 1, wherein the temperature sensitive switches of the sensor network are electrically connected in series, and the sensor network is configured to provide the overheat signal if a measurement voltage and/or a measurement current is not present at a measurement terminal.
8. A compressor assembly according to claim 1, wherein the temperature sensitive switches of the sensor network are electrically connected in parallel, each temperature sensitive switch is arranged in a parallel branch of the sensor network, a measurement terminal is arranged in one of the parallel branches, and the sensor network is configured to provide the overheat signal if a measurement current at the measurement terminal changes.
9. A compressor assembly according to claim 8, wherein at least two parallel branches comprise a resistor with a resistance, wherein a first resistance of a first resistor in a first parallel branch differs from a second resistance of a second resistor in a second parallel branch.
10. A compressor assembly according to claim 7, wherein the overheat signal is representative for the measurement current at the measurement terminal of the temperature sensitive switch where the switch temperature is exceeded.
11. A compressor assembly according to claim 1, wherein the sensor network comprises a signal processing unit, adapted to provide the overheat signal in dependence of the measurement voltage and/or a measurement current, wherein preferably the signal processing unit is connected to an electronic control unit of the commercial vehicle.
12. An air supply system for a commercial vehicle, comprising a compressor assembly according to claim 1.
13. A commercial vehicle, comprising:
  - at least one pneumatic consumer, and
  - a compressor assembly according to claim 1.
14. A commercial vehicle according to claim 13, comprising an electronic control unit connected to the sensor network, in particular to a signal processing unit, adapted to receive an overheat signal and to provide an alarm indication via an alarm indication device, preferably to display an alarm message, in dependence of the overheat signal.
